MACHINE FOR SIZING TUBES

Lester H. Messinger, Trumbull, Conn., assignor
to Remington Arms Company, Inc., Bridgeport,
Conn., a corporation of Delaware

Application June 23, 1945, Serial No. 601,273

16 Claims. (Cl. 93—83)

1

This invention relates, in general, to a machine for sizing tubes, and, more particularly, to a machine for sizing paper tubes for the manufacture of shot shells.

In the art of making paper tubes for shot shells, it is necessary that the tubes be both straight and of a predetermined outside diameter to within very close tolerances. Since the paper tube is a relatively soft semi-rigid structure, it is necessary that the tube be properly supported during the sizing operation. Moreover, in the event a tube is malformed or improperly fed to the machine or collapses under stress, it is desirable that the machine be stopped immediately to prevent jams and the loss of additional tubes. Further, for economical reasons, it is desired that the greatest possible number of tubes be sized in a minimum amount of time; that the sizing apparatus be readily adapted for sizing both a smooth surfaced tube or tube having longitudinal corrugations and that tubes of different sizes be sized simultaneously on a single machine.

An object of the present invention is, therefore, the provision of an improved paper tube sizing machine capable of sizing tubes at an extremely rapid rate. A further object is the provision of a tube sizing machine which may be readily adapted to size both smooth surfaced and fluted tubes and to size tubes of different size simultaneously. A further object is to provide a tube sizing machine having improved means for supporting the tubes and advancing the tubes into the sizing dies. A still further object is to provide a tube sizing machine with improved means for automatically stopping its operation in the event abnormal conditions develop.

These and other objects, features and advantages of the invention will be disclosed in greater detail in the following specification taken in conjunction with the accompanying drawings, in which:

Fig. 1 is a fragmentary front elevation showing the left end of the machine including details of the hydraulic system.

Fig. 1a is a fragmentary front elevation of the machine being a continuation of the left end of the machine shown in Fig. 1.

Fig. 1b is a fragmentary front elevation showing the right end of the machine and being a continuation of the portion shown in Fig. 1a.

Fig. 2 is a plan view of that portion of the machine shown in Fig. 1.

Fig. 2a is a plan view of that portion of the machine shown in Fig. 1a.

2

Fig. 2b is a plan view of that portion of the machine shown in Fig. 1b.

Fig. 2c is a reduced side elevation partly in section of the die holder and lubricant tank in the direction of arrows 2c—2c of Fig. 2a.

Fig. 3 is a fragmentary plan view partly in section of one of the mandrel carriages shown mounted on a pair of rails.

Fig. 4 is a fragmentary side elevation partly in section of the carriage shown in Fig. 3.

Fig. 5 is a fragmentary back elevation of a portion of the machine showing part of the hopper stack for delivering tubes into the hopper; and details of the sizing dies and die lubricating means.

Fig. 6 is a fragmentary side elevation in the direction of the arrows 6—6 of Fig. 5.

Fig. 7 is a fragmentary side elevation in the direction of the arrows 7—7 of Fig. 5.

Fig. 8 is a fragmentary side elevation of details of the feed mechanism for controlling the delivery of the sizing tubes to a basket.

Fig. 9 is a fragmentary side elevation of the limit switch and cam operating means in the direction of arrows 9—9 of Fig. 2.

Fig. 10 is a diagram of the electrical circuit for controlling the operation of the machine. Fig. 11 is a fragmentary longitudinal sectional elevation of a sizing dye and its holder.

The terms "front" and "back" as hereinafter used with respect to the machine shall be understood to refer to the parts thereof adjacent the bottom and top margins respectively of the drawings (Figs. 2, 2a and 2b); the "left" end and "right" end of the machine being identified with the left and right margins respectively. The terms "forwardly" and "rearwardly" as used in connection with a carriage mean its movement towards and from the sizing dies respectively.

In general, the machine embodies a horizontal bed having two longitudinally spaced carriages movable thereon in unison and in the same direction, each carriage having a plurality of rotatable mandrels arranged in a substantially horizontal plane parallel to the bed of the machine and extending longitudinally thereof, the free ends of one set of mandrels being opposed to the free ends of the second set of mandrels. Located at the center of the machine between the opposed

ends of the two sets of mandrels are two sets of sizing dies and a pair of hoppers, each hopper being adapted to supply a plurality of tubes successively in axial alignment with one set of mandrels and one set of sizing dies. The carriages are actuated so that as one set of mandrels is

advancing into its allotted tubes and pushing these tubes through the adjacent set of sizing dies, the second carriage is receding simultaneously stripping a plurality of sized tubes from its set of mandrels. The carriages are reciprocated continuously by a hydraulically driven piston rod, the sized tubes being collected in suitable baskets arranged beneath the bed and adjacent each hopper.

Machine bed

Referring to the drawings, Figs. 2, 2a and 2b show a plan view of the machine which comprises a substantially rectangular bed made up of steel channel members, the side channels 15 being substantially seven and one-half times longer than the end channels 16. The bed is supported at its ends and at suitable intermediate points by a plurality of vertical leg members 17 held rigidly by suitable braces 18 as shown in Figs. 1, 1a and 1b. The channel members, legs and braces may be secured together by a suitable means as, for example, by bolts or by welded joints so as to form a rigid structure. Although steel channels and angle bar stock are shown in the present embodiment, it will be understood that the frame and bed may comprise structural members of other forms.

Mounted rigidly on the inside of the side channels 15 at substantially right angles thereto and at longitudinally spaced points are four brackets 19, the longitudinal axes of which lie in a common plane coincident with the horizontal plane of the bed. Each bracket comprises a boss 20, the longitudinal axis of its bore being substantially parallel to the longitudinal axis of the bed.

Referring to Figs. 2a and 2b mounted between each pair of axially aligned brackets is a tubular supporting member 22, the opposite ends 23 of each tubular member being adapted to make a press fit in the bore 20 of its respective bracket. Within each end 23 of the two spaced parallel tubular supporting members 22 is a bushing 24 (see Figs. 6 and 7). Mounted so as to have a smooth running fit in each pair of longitudinally spaced, axially aligned bushings 24 is an elongated carriage-supporting and actuating rod 25 which, as clearly shown in Fig. 8, has a free fit within the corresponding tubular supporting member 22. The ends of each rod 25 extend both to the right and left respectively beyond the bushings 24, the extremity 25' of each rod being of reduced diameter (see Figs. 3 and 4) so as to fit into a socket or aperture 28' at one end of a carriage. As shown, a pair of carriages are arranged transversely of the longitudinal axis of the bed, each carriage being drawn up tightly against substantially square shoulders 26 at the extremities 25' of the rods 25 by means of suitable nuts 27 secured on the threaded ends thereof. Each carriage is thus wholly supported between the spaced side channels 15 of the bed and at the extreme ends of the spaced parallel reciprocably mounted rods 25.

Mandrel carriage

The carriages are identical and hence a description of one will suffice for both. Referring to Figs. 3 and 4, each carriage comprises a substantially rectangular block 28 having apertures 28' for receiving the reduced ends 25' of the carriage rods 25. A substantially rectangular recess 29 is provided in the top of each block, which recess, in conjunction with a cover 30, is adapted to form a gear box for housing the worm wheels of the

mandrels and the cooperatively engaged worm gears of a drive shaft. The drive shaft 32 is coincident with the longitudinal axis of the carriage being rotatably supported at its opposite ends in suitable bearing blocks 33 which in the present embodiment are integral with the carriage. It will be appreciated, however, that the bearing blocks 33 may constitute separable members secured by bolts or other fastening means to the top of the carriage. The drive shaft 32 of the carriage shown at the left end of the machine (Fig. 2a) is extended rearwardly and provided with a suitable drive pulley 34 which is fastened securely thereto. The drive shaft of the carriage shown at the right end of the machine (Fig. 2b) is provided with a similar pulley 34, but, in this instance, the shaft extension and pulley are at the front of the machine.

Each drive shaft 32 is provided with a plurality of worm gears 35, five gears being shown in the present embodiment, each being keyed to the shaft 32 and kept in spaced relationship thereto by means of floating collets 350. The worm gears are adapted to cooperatively engage the teeth 36 of suitable worm wheels 37, each of which is keyed to the hub 38 of one of five tube supporting mandrels. The hub portion of each mandrel is mounted in apertures 39 and 40 extending through the side walls of the carriage 28 at substantially right angles to its longitudinal axis. The apertures 40 in one wall of the carriage are of greater diameter than the apertures 39 and counterbored to receive a flanged sleeve 42 which is fastened in the counterbored aperture 40 by suitable bolts 43. The bushings for the apertures 39 and the flanged sleeves 42 are indicated at 44. An end thrust bearing 45 (see Fig. 3) is provided on each mandrel between a shoulder 38' of its hub 38 and the adjacent wall of the gear box 29.

The assembly of worm gears and worm wheels is enclosed within the gear box 29 by the cover 30 which is removably secured to the carriage by bolts 31. The cover is also provided on its underside with integral transverse vertically depending spaced parallel webs 300, the bottom edges of which are substantially semicircular and adapted to embrace the floating collets 350 to provide rigidity to the shaft and prevent whipping.

Each shaft 32 is adapted to be driven by a belt 46 connecting its pulley 34 with a pulley 47 of a drive motor 48, the latter being suitably supported on the underside of each carriage.

The tube supporting mandrels are preferably made in two sections, the free ends 380 of the mandrels being joined to the shank portions 380' by an internal screw threaded connection. At the joint which defines each connection, there is a suitable collar or shoulder 381, the diameter of which is greater than the inside diameter and slightly less than the outside diameter of a tube T (Fig. 11) to be sized so as to enable the shoulder to engage an end of a tube to push the tube through a sizing die, the shoulder itself moving completely through the die during the sizing operation.

Sizing dies

A set of sizing dies is provided for the mandrels of each carriage. In the present embodiment, each die 49 actually comprises two die members 490 and 491 assembled in axial alignment (see Figs. 5 and 11), but it will be understood that a single die piece may be used. By

providing a die comprising two separate die elements, the profile of each die piece may be more accurately maintained.

The dies of each set are each supported in a die holder 50 (see Fig. 2c) which spans the two tubular supporting members 22 and is substantially L-shaped in cross section (see Fig. 5) being provided with a longitudinal passage 52 closed at each end by suitable screw plugs for lubricating purposes as hereinafter described. The substantially vertical rib portion 53 of each die holder has spaced semicircular notches 54 which constitute supporting pockets for each die 49.

To facilitate removal and replacement of the dies, each is held in its pocket 54 by an inverted U-shaped yoke 55, the slot 55' of which is substantially rectangular in shape so as to fit closely over the substantially rectangular rib portion 53 of the die holder 50. The face of each yoke toward which its respective spindle moves, being the right-hand face of the die as seen in Fig. 5 is provided with an aperture 56, the throat of which converges inwardly toward the center of the die. The opposite face of the yoke is provided with a substantially rectangular vertical slot 57, as shown in Fig. 2c. The top of each yoke 55 offers a substantially flat surface for a tie bar 58 which is adapted to span all of the yokes 55 of the die holder and to be held down securely against the flats of the yokes by adjustable fastening means so as to hold each die securely in its pocket 54 against both longitudinal and vertical displacement. To this end, one end of the tie bar 58 is pivoted as at 59 to the upper element or cap 60 of a clamp (see Fig. 2c) which is fastened securely by bolts 60' around one of the fixed tubular members 22. The clamp is adapted to securely support the adjacent end of the die holder 50 as indicated in Fig. 2c. The opposite end of the tie bar is adapted to be swung into position into a relief slot 62 provided in the cap of a second clamp 63 which is fastened securely by bolts 63' to the opposite tubular member 22, the clamp 63 being adapted to securely support the other end of the die holder 50. A knurled headed screw 64 is provided for fastening the end of the bar 58 in the relief slot 62. Reference to Figs. 2a and 2b shows two identical sets of clamping members 60 and 63, yokes 55, tie bars 58 and transverse die holders 50, each located at substantially equal distances from the longitudinally spaced brackets 19 of the bed.

Die lubrication

Referring to Figs. 2c and 5, the bottom of each die holder 50 is supported within the open top of a transversely disposed oil trough 65 which is substantially rectangular in cross section and rigidly secured to the bed. A pipe line 61 having a one-way ball check valve 610 is connected by means of a nipple to one end of the longitudinal passage 52 of the die holder 50 and is adapted to supply oil under pressure to the passage 52, suitable oil pump means being provided for this purpose as hereinafter described. The oil flows under pressure up into a plurality of transversely spaced nozzles 66, each of which is mounted in an aperture in the ledge 51 of the holder in communication with its longitudinal passage 52 and substantially opposite one of the dies 49. During the tube sizing operation, each nozzle is adapted to discharge oil onto its respective die, the dispersed oil running back into the trough 65. The oil in the trough is carried away by means of a return pipe line 61' connected at one end to

the bottom of the trough and at its opposite end by means of a second ball check valve 610' to the pipe line 61, thereby forming a closed circuit. The oil held in the tank 65 is maintained at a substantially constant level by a reservoir tank (not shown) which is connected by a pipe 65' to the bottom of the trough 65.

Hoppers

Between each set of dies 49 and the ends of the corresponding set of mandrels 380 (see Figs. 2a and 2b) is a hopper indicated generally at 70 which is adapted to deliver tubes successively and in axial alignment with the mandrels and dies. In Fig. 2b, the mandrels 380 have been advanced through their respective hopper and dies and are about to be withdrawn in the direction of the arrow.

Tubes are delivered to each hopper 70 from a stack 72 to which the tubes are fed in any suitable manner and in properly oriented relationship. Each hopper 70, (see Figs. 6 and 7) comprises a substantially rectangular box structure comprising a base block 73, right and left end panels 74 and 75 respectively preferably of a substantially rigid transparent material such as Lucite, and front and rear panels 76 and 77 respectively. The rear panel is shown provided with a hinged door 78 which extends substantially the full width of the hopper. The door may be constructed of a relatively thin metal and is shown formed with an inwardly projecting elbow portion 79 which in conjunction with a curved plate 80 extending across the front of the hopper and on the inside thereof, serves to guide the free fall of the tubes from the stack 72 into the hopper.

The base blocks 73 of each hopper is fastened on the top edges of a pair of wooden stringers 82 which are bolted to a pair of angle iron members 83. The latter span the side channel members 15 and are secured at their opposite ends thereto by welded joints or similar fastening means.

As shown in Figs. 6 and 2a, the base 73 of each hopper comprises a substantially rectangular block provided with a plurality of spaced parallel longitudinally extending grooves 84 having substantially vertical walls and a V-shaped bottom 85. Each of these grooves is arranged in axial alignment with one of the dies and its corresponding spindle 380. Suitable apertures are provided in each Lucite end panel of the hopper opposite one of the grooves, the apertures in the panel at the left side being substantially vertical slots 86 arcuate at the bottom as shown at 86'. The apertures in the Lucite panel at the right side of the hopper (see Fig. 7) are substantially circular holes 87.

The slots 86 are shown provided with gates 88 each comprising an elongated substantially rectangular member having an arcuate lower edge. The upper end of each gate is fastened to a bar 89 which is supported substantially horizontally by a pair of hinges 90 across the end panel 74 of the hopper. The left end of the bar extends beyond the front edge of the hopper as shown in Fig. 6 and is provided with a pin 92 substantially perpendicular to the vertical plane of the gate 88 and extending to the right as viewed in Fig. 5. A coil spring 93 is connected at its lower end to the extremity of the pin 92 and at its upper end to a pin 94 projecting from a wooden end member 95 at the upper edge of the hopper whereby the hinged gates are spring biased to resist displace-

ment from their vertical plane. It will be clear, however, from Fig. 5, that the gates may swing clockwise with the hinged bar 89.

The opposite end of the bar 89 extends beyond the rear edge of the hopper and is provided with a depending arm 96 adapted normally to be held by the force of the spring 93 in engagement with a push button 97 of a micro-switch 98 which is shown fastened securely to the back of the hopper. The switch 98 is part of an electrical circuit controlling the reciprocation of the spindle carriages and is normally closed. Thus, in the event a tube in the hopper is improperly oriented so as to be out of axial alignment with a die or its mandrel, the tube will in all probability be pushed against one of the gates 88 so as to displace the latter outwardly, thus pivoting the bar 89 clockwise and withdrawing the switch arm 96 from engagement with the switch button 97. The circuit will thus be opened thereby stopping the movement of the carriage so as to prevent further malfunctioning. After the defective or misaligned tube has been removed, the gates will swing back to their normal position and the switch 98 will be closed.

Each hopper is provided at its opposite end (see Fig. 5) corresponding to the end toward which the mandrels advance with an L-shaped bracket member 99 which extends across the end of the hopper and is provided with a plurality of spaced substantially vertical slots 100 in alignment with the V-shaped grooves 84 in the hopper bottom. In each slot 100, a cylindrical roller 102 is rotatably mounted, all of the rollers being supported on a single shaft 103 extending through a transverse longitudinal aperture of the bracket 99. The upper edge of each roller is adapted to be tangential to the lower edge of each mandrel 380 and to constitute antifriction supporting means therefor.

Each hopper is provided with means for delivering the tubes successively into the grooves in the hopper bottom; and with means arranged whereby a tube in a groove in the hopper bottom will be out of contact with the tube immediately above it, thus eliminating any abrading action between the tubes as the lower tube is pushed out of the hopper by its respective mandrel.

The tube delivering means of each hopper comprises a plurality of oscillating baffle members 104 which extend lengthwise of the hopper (see Fig. 5) and which are substantially triangular in cross section, all edges of the members being rounded as shown in Fig. 7. Each baffle member is pivotally supported at its opposite ends by suitable pins 105 which extend through suitable holes in the Lucite end panels. The pins 105 adjacent the end 75 of the hopper (see Fig. 5) and corresponding to the end which is approached by the advancing spindle 380 are longer than the pins at the opposite end of the hopper, each being extended beyond the face of the Lucite panel to support a crank member 106 which is secured to the pin. Each crank has an upwardly extending slotted arm 106' adapted to accommodate the lower edge of a connecting bar 107 which extends transversely across the end of the hopper. Suitable fastening means such as pins 108 pivotally connect each crank arm 106' to the bar 107. The bar 107 is spring biased by a coil spring 109 which, in the hopper shown at the left-hand end of the machine (see Fig. 2a), is fastened at one end to the front edge of the bed and at its opposite end to the front end of the bar 107. The baffle controlling bar 107 in the hopper at the right end

of the machine (see Fig. 2b) is spring biased in the opposite direction, that is by a coil spring fastened to the back edge of the machine.

The bars 107 are adapted to be given a slight forward and backward movement to oscillate the baffle members 104. To this end, each bar 107 is provided with a rigid pin 1090 which is located at substantially its center and projects outwardly at substantially right angles to the vertical plane of the bar 107. Each pin 109 is adapted to be engaged by the forked end 110 of an actuator 112, the forked end of which is bent downwardly at substantially right angles thereto as shown in Fig. 5. The rear end of the actuator 112 is pivotally secured as at 113 to the corresponding end of the machine bed. One edge of each actuator comprises a cam surface indicated generally at 114 which is adapted to be held in cooperative engagement with a suitable cam roller 115 mounted on the top of the corresponding carriage by the force of the tensioned coil spring 109. Thus, as each carriage reciprocates, each actuator is pivoted slightly about its pivot 113 providing relatively short reciprocating movement to its respective bar 107 and hence oscillating the several baffle members 104 simultaneously in the same direction and in timed relationship to the movement of the carriage.

The devices for temporarily holding successive tubes out of engagement with a tube delivered into a groove of the hopper bottom comprise a pair of hook-shaped elements 116 secured to each baffle member 104, one hook being at each end thereof. The reach 116' of each hook is set into a suitable indentation or recess provided in the face of the baffle member, the hook 116 being adapted to extend into the adjacent groove 84 (see Fig. 2a). The hooks 116 are adapted, however, to extend into the respective grooves only when the baffle member 104 has been oscillated to the position shown in Fig. 7, that is to say, when the connecting bar 107 has been moved to the left by the advancing movement of the carriage. It will be seen that, when the hooks extend into the grooves 84, each pair of hooks supports a tube T above and spaced from a tube T lying in the bottom of its respective groove. Following the removal of the tubes from the grooves by the sizing operation and the subsequent stripping action, the carriage is withdrawn to the end of its rearward stroke drawing the mandrels back through the sizing dies and the empty grooves of the hopper bottom, whereupon the connecting bar 107 is released by the actuator 112 and drawn to the right by the spring 109 thereby oscillating the baffle members 104 clockwise and moving the hooks 116 out of the grooves 84. Sufficient movement of the hooks to prevent obstruction of the grooves is permitted by providing substantially rectangular relief recesses 117 in the ribs of the hopper bottom separating the respective grooves 84. As the hooks 116 recede, the tubes supported thereon drop down into their respective grooves and then as the carriage again moves forward, the connecting bar 107 is actuated so that the hooks push between the tube T which is in a groove and the tube T supported thereon and lifts the latter upwardly out of engagement with the tube in the groove.

Discharge chutes

Between the two sets of sizing dies 49 are a pair of tube discharging elements indicated generally at 118 in Fig. 8. Each tube discharging element comprises a substantially rectangular

box 119, one side 119' of which is lower than the other three sides and located adjacent the exit ends of the sizing dies 49. The box is supported by means of a pair of spaced parallel straps 120 which are fastened to the top edges of the box, the opposite ends 122 of each strap being adapted to rest on and to be bent partially around the adjacent fixed tubular member 22 as shown in Fig. 8. A screw 122' is shown for fastening the straps 120 to the tubular members 22. By this arrangement, the upper edge of the side 119' of the box is located slightly below the longitudinal axes of the dies and mandrels so that tubes being stripped from the mandrels will pass into the box 119.

The box 119 is shown divided into separate compartments or chutes by partitions 123, each partition and the corresponding sides of the box 119 being provided with suitably inclined baffle plates 124 to control the free fall of the tubes into the bottom of their respective chutes.

From the bottom of the chutes the tubes are adapted to be delivered into suitable baskets 125. It is desirable, however, to close the bottom of each chute whenever the basket is removed so as to prevent the tubes from falling onto the floor. To this end, the bottom of each chute is provided with a trap door 126, each door being secured at one edge to a rod 127, the ends of which are rotatably supported in apertures in opposite walls of the box. Each rod is extended beyond one wall of the box and provided with a slotted crank arm 128 in the slot of which is mounted a connecting bar 129, the latter being secured to each crank arm 128 by pins 130. The connecting bar 129 may be provided with a handle 130 and is spring biased by a coil spring 132 in an obvious manner so as to hold the trap doors 126 closed. One end of a lever arm 133 is connected at the right-hand end of the bar 129 (Fig. 8), the lever 133 being pivotally supported intermediate its ends in a fixed bracket member 134. The lower end of the lever 133 is adapted to extend into the space which is occupied by a portion of the rim of the basket when the latter is in place. Consequently, when the basket is in position beneath the chutes, the lever arm 133 will be pivoted counterclockwise thus moving the connecting bar 129 to the left against the resisting force of the spring 132 and opening the trap doors 126. When a full basket is removed, the trap door is immediately closed. A fixed stop 135 is provided to position the basket beneath the chutes.

Carriage control

The mandrel carriages are both securely mounted at opposite ends to the reciprocable rods 25 as described above, the rods and carriages being movable as a unit by means of a hydraulically operated piston rod.

Referring to Figs 2 and 2a, the carriage 28 at the left end of the machine is provided with a yoke 136 which is secured thereto in substantially the horizontal plane thereof. The transverse portion of the yoke is provided with an aperture 137, the axis of which is in axial alignment with the longitudinal axis of the bed and in substantially the horizontal plane of the carriage. This aperture 137 is adapted to receive the forward end of a piston rod 138 which extends through the aperture of the yoke, its end being reduced and threaded to take a nut 139 for securing the rod to the yoke.

The piston rod 138 extends to the left end of the machine through an axially aligned aperture

of a transversely disposed bolster 140 which is firmly secured at its opposite ends to the side channels 15 as shown in Figs. 1 and 2. The bolster 140 constitutes the support for the forward end of a hydraulic cylinder 142. The piston rod is reciprocably mounted in the hydraulic cylinder, the outer face of the head (not shown) of the piston rod being substantially twice the area of its inner face, the area of the inner face being reduced by the diameter of the piston rod. The rear end of the hydraulic cylinder 142 is supported in any suitable manner by a second transverse bolster 143. Between the two bolsters 140 and 143 is a transverse brace 144 which is secured at its opposite ends to the two side channels 15. The brace 144 is adapted to provide a bearing support for a roller 145 which in turn constitutes a support for a rod 146, the rear end of which is substantially free. The forward end of the rod 146 is adapted to be secured to the carriage 28 by a threaded portion 146' secured in a threaded aperture of the carriage 28 (see Fig. 2a) and held by a lock nut 147. The periphery of the rod 146 is provided with longitudinally extending cam surfaces constituting longitudinal flats 148 and 148' (see Fig. 9) disposed at an angle of substantially 75° to each other and adapted to be engaged by suitable cam rollers 149 and 149' respectively, each of which is carried on the lower end of an arm 150 and 150'. The arms 150 and 150' are secured at their upper ends to the opposite ends respectively of a switch actuating shaft 152 which is rotatably mounted in a switch box 153 supported by a bracket 154 above the rod 146. A finger 155 is shown fastened to the arm 150 at the extreme end 156 of which is fastened one end of a coil spring 157, the opposite end of the latter being secured to the fixed bracket 154. The line of action of the force of the spring 157 is normally off center with respect to the pivoted arms 150 and 150'. Thus, the roller 149' is held firmly in engagement with the flat 148' by the spring 157, the line of force of which is above the pivot pin 152 when the rod is in the position shown in Figs. 2 and 9. When the rod 146 is moved forwardly so that the roller 149' rides up on the periphery of the rod, the roller 149 will then be held firmly in engagement with its corresponding flat 148 by the spring 157, the line of force of which is now below the pivot pin 152.

The switch 153 is hereinafter termed a "limit switch" and is normally held in its "on" position by either position of the rollers 149 and 149' respectively. However, during the brief period in which the rollers transfer their respective positions relative to the rod, the switch is momentarily open and, if at this same instant an abnormal load condition exists in the operation of the machine, the carriages will be automatically stopped as hereinafter described.

The carriage 28 at the left-hand end of the machine also supports a second rod which is adapted to actuate a carriage reversing valve. This rod is shown at 1550 (Fig. 2) and is provided with a collar 1560 at its extreme left end, the latter being free and unsupported. The forward or right end of the rod 1550 passes through a guide aperture of the bolster 140 and is secured in a threaded hole in the carriage being secured therein by a nut 1570, as shown in Fig. 2a. Fixed to the forward end of the rod 1550 is a substantially vertically disposed bracket 158 in which is adjustably secured the forward end of a rod 159 of relatively small diameter, the rear end of which

extends in a plane substantially parallel to the horizontal plane of the rod 1550.

The rod 1550 and the rod 159 are adapted to automatically actuate a carriage reversing valve 160 which is suitably designed to reverse the direction of flow of oil to the hydraulic cylinder 142. Assuming the valve 160 is set so that the mandrel carriages are being moved to the right, then when the collar 1560 of the rod 1550 strikes the pin 162 (see Fig. 1) of the rotatable valve head 164, the latter will be actuated to reverse the direction of flow of fluid to the hydraulic cylinder 142. The carriages then move to the left until such time as the left end of the rod 159 contacts the pin 163 of the valve head 164. Thereupon, the latter is rotated and the direction of movement of the carriages is again reversed. A suitable handle 165 is shown on the valve head 164 for manually controlling the direction of movement of the carriages.

Lubricating pump

It is necessary that each set of sizing dies be flooded with lubricant during the sizing operation. It is preferable, however, that the flow of lubricant shall begin just before tubes and mandrels have actually entered the dies; and that the lubricant be shut off just before the mandrels and tubes pass out of the dies so as to insure that no lubricant will be sprayed onto the bare mandrels or drip onto the mandrels as they are withdrawn from the dies following the stripping of the sized tubes.

A suitable pump is provided at each end of the machine for pumping lubricant to the die nozzles 66 (see Fig. 5). Referring to Figs. 1 and 1a, the pipe line 61 which is part of a closed circuit for feeding oil to the nozzles 66 is connected by a coupling 170 to the head end 172' of a cylinder 172 which contains the lubricant and which is supported on the underside of the adjacent channel 15 by a pair of hangers 173. A packing gland 174 is fastened at the rear end of the cylinder 172 and provides guide means for the forward end of a piston rod 175 which is adapted to be moved into and from the cylinder 172. The piston rod is relatively long being supported at its left or rear end by a bushed bracket 176 secured on the underside of the bolster 140 as shown in Fig. 1.

Fastened to the rod 175 forwardly of its supporting bracket 176 is a collet 177 which constitutes a stop for an enlarged cup-shaped collar 178 (Fig. 1) which is slidable freely on the rod. The interior walls of the collar 178 are threaded for threadedly securing the rear end of a tubular member 179 therein. The tubular member 179 extends forwardly on the rod 175 being provided at its forward end with an annular flange 180. The interior diameter of the tubular member 179 is sufficiently greater than the outside diameter of the rod 175 so as to provide an annular space therebetween in which is placed a coil spring 182, the rear end of the latter being adapted to seat against the base of the cup-shaped collar 178. The forward end of the spring 182 abuts the rear end of a short sleeve 183 carried on the rod 175. The rear end of the sleeve 183 is shown telescoped within the forward end of the tubular member 179 and is provided at its forward end with an annular flange 184 having a set screw 185 for securing the sleeve to the piston rod 175. Supported on the underside of the spindle carriage 28 is a bracket 186 provided with an apertured boss 187 which is slidable freely on the tubular member 179.

As the carriage 28 moves forwardly or to the right (Fig. 1a), the boss 187 rides freely over the tubular member 179 until it engages its annular flange 180 and thereafter the boss picks up the tubular member 179. The distance through which the boss moves before contacting the flange 180 corresponds substantially to the distance the forward end of each spindle must move to enter its respective sizing die. During this interval, there has been no flow of lubricant to the dies.

When, however, the boss picks up the flange 180, the cup-shaped collar 178 moves forwardly on the piston rod, its movement being resisted by the force of the coil spring 182 which bears at its forward end against the rear end of the sleeve 183. The spring 182 is relatively light and hence is compressed. There is, therefore, a certain amount of lost motion between the movement of the tubular member 179 and the subsequent movement of the piston rod 175 due to the compression of the spring. However, following the compression of the spring, the flange 180 of the tubular member engages the flange 184 of the sleeve 183 and since the latter is fastened to the piston rod 175, the rod is positively pushed forward into the cylinder 172 forcing lubricant from the nozzles 66 over the sizing dies. At the forward end of the stroke, the mandrels will have pushed the sized tubes entirely through the dies. However, just before this point is reached, the flange 184 of the sleeve 183 contacts an adjustable part 174' of the fixed gland 174 to positively stop further movement of the piston rod and hence to cut off the flow of lubricant to the dies.

At the start of the subsequent rearward movement of the carriage the tubular member 179, by reason of the force of the compressed spring 182, moves back immediately hugging the rearwardly moving boss 187 until the cup-shaped collar 178 engages the collet 177. Thereafter, the boss 187 moves rearwardly relative to the tubular member 179 a distance corresponding to the distance between the flange 180 and the collar 178, after which the boss 187 picks up the mutually engaging collar 178 and collet 177 and hence positively withdraws the piston rod from the cylinder. This action sucks the overflow oil from the trough 65 back into the cylinder 172 by way of the pipe 61.

The piston rod and cylinder at the right end of the machine are substantially identical in operation to the apparatus described above, but has been modified in some respects to reduce the overall length of the piston rod. The rear ends of the piston rods must be adequately supported and such support is given for the rod 175 at the left end of the machine by providing it with a relatively long rear end portion slidably in an aperture of the fixed bracket 176. The rear end of the piston rod 175 at the right end of the machine is not extended but is slidably supported in the central aperture of a transverse yoke 175' which is slidably supported at its opposite ends on a pair of fixed guide rods 188. The yoke 175' is provided with an internally threaded hole in which is secured the rear end of a tubular member 179 corresponding to the tubular member 179 at the left end of the machine; and a coil spring 182 to provide a resilient connection between the yoke 175' and a flanged sleeve 183 (not shown) secured to the piston rod 175.

Mandrel drive

As described above, all the mandrels of each

carriage are adapted to be driven simultaneously by a motor gear drive, the motor unit 48 being supported on the underside of each carriage.

There are at least two well known types of shot shell tubes, the one having a smooth surface and the other being fluted longitudinally. In sizing tubes for fluted shells, the mandrels must not be rotated. Moreover, in sizing smooth surfaced tubes, it has been found preferable to rotate the mandrels only during the sizing operation and to stop the rotation of the mandrels during the tube telescoping and stripping operations.

To these ends, each carriage 28 is provided at one end with a limit switch. The limit switch for the carriage at the left end of the machine is located at the front end of the carriage as indicated at 193 in Fig. 2a, the switch on the carriage at the right end of the machine being on the back end thereof (Fig. 2b).

Each switch is adapted to have an electric conduit attached thereto as at 192 and a laterally extending crank arm 193 for closing and opening the switch terminals. Each crank arm 193 is provided with a roller 194 which is adapted normally to ride on a substantially horizontal track 195 secured on the inside wall of the adjacent channel 15. In the normal position of the roller 194, the switch is off and the mandrels will not rotate. The roller maintains its normal position throughout the entire rearward movement of the carriage during a part of which tubes are being stripped from the mandrels; and through substantially the first half of the forward movement corresponding to the tube telescoping operation. Thereafter the roller 194 rides up a hinged inclined ramp 196 which carries the roller up onto an elevated track 197 in the vertical plane of the track 195, but spaced above it a distance slightly greater than the diameter of the roller 194. The upward displacement of the roller 194 actuates its crank arm 193 to close the switch 190, thus causing the mandrels to rotate. The roller continues along the upward track 197 until the carriage has reached the end of its forward stroke. At substantially this point, the upper track 197 ends as indicated at 197' and the roller 194 being no longer supported drops down onto the lower track 195 whereupon the switch arm 193 moves to its normal switch opening position and the mandrels cease to rotate. During the subsequent rearward movement of the carriage, the roller 194 moves back along the lower track 195 beneath the upper track 197, the hinged inclined ramp 196 being free to swing up as the roller passes beneath it.

Hydraulic system

The hydraulic unit for actuating the carriage piston 138 is shown in detail in Figs. 1 and 2 and comprises an oil sump 200 above which is mounted a suitable power unit or motor 202 connected to an oil pump 203 which is adapted to draw oil from the sump 200 and deliver it to either end of the hydraulic cylinder 142. The oil is adapted to be conducted to the right end of the cylinder by a main pipe 204 and to the left end of the cylinder by pipes 205 and 2050. A four-way valve 206 is provided between the pipe lines 205 and 2050 and has a return pipe 207 adapted to deliver oil directly from the pipe 2050 into the sump 200. A relief valve 208 is connected between the main pipe line 204 and the pump 203 having a connection 209 to the return pipe 207.

Assuming the left-hand carriage is at the extreme right-hand end of its stroke (see Fig. 1),

then when the oil is pushed through the main pipe line 204 to the right-hand end of the cylinder, the piston rod 138 will be driven to the left, the oil in the left end of the cylinder flowing freely through the pipes 2050, the four-way valve 206 and the return pipe 207 back into the sump 200. As the carriage approaches the left end of the machine, the valve actuating rod 159 will engage the pin 163 and trip the reversing valve 160 as described above. The latter is connected by suitable feeder pipes *a* and *b* to the four-way valve 206; by the pipe *c* to the relief valve 208 and by the return pipe *d* to the sump. The actuation of the reversing valve 160 automatically actuates the four-way valve to close the pipe 207, and hence to prevent the flow of oil from the left end of the cylinder back into the sump 200. As a consequence, oil pressure builds up at both ends of the hydraulic cylinder, but since the area of the piston head on which the oil pressure from the pipe 2050 acts is substantially twice the area of the piston head against which oil from the pipe 204 acts, the force acting on the piston to push it to the right exceeds that force tending to move it in the opposite direction, and hence the piston rod moves to the right and oil in the right-hand end of the cylinder is displaced back through the pipe 204 up into the four-way valve 206 and into the left end of the cylinder. When the carriage reaches the end of its stroke to the right, the aforementioned collar 1560 of the rod 1550 will contact the pin 162 of the reversing valve 160 and again trip the valve whereupon oil being delivered to the left end of the cylinder is allowed to escape by way of the pipe 207 into the pump and pressure builds up in the right-hand end of the cylinder pushing the piston rod 138 to the left.

A suitable pressure indicator pipe *e* is shown connected in the pipe section 205 between the relief valve 208 and the four-way valve 206 and is shown provided with three hydraulic pressure switches A, B and C for the purpose hereinafter described. These pressure switches are shown within the frame of the machine (Fig. 1), but it will be understood that the length of the pipe *e* may be extended so as to permit mounting the switches A, B and C on a suitable panel or buss board (not shown) together with the switches and line starters of the electrical circuit.

Electric circuit

Fig. 10 shows diagrammatically the electrical circuit for controlling the operation of the machine. The main knife switch is shown at M having leads connected to a conventional line starter L. Leads from the starter L are connected to a starter button S, to the pump motor 202 and the hydraulic pressure switches A, B and C, the function of which is as follows:

The switch A is adapted to open whenever the pressure in the line *e* falls below a minimum pressure such as when the carriages are reciprocating under no load conditions. If for any reason the load on the carriages is or drops below this minimum operating pressure, switch A will automatically open and the machine will be stopped, the circuit to the pump motor 202 being opened. In order to start the machine, the operator must hold the starter button S until a pressure in excess of the minimum operating pressure builds up in the hydraulic system whereupon the switch A closes and the operator may then release the starter button.

The hydraulic switch B is normally closed, but

is adapted to open the circuit in the event the pressure in the hydraulic system exceeds a maximum operating pressure which in the present embodiment is substantially five hundred pounds; thus, in the event one or more tubes becomes jammed thereby causing the hydraulic pressure to rise, then, at an upper safe limit of five hundred pounds, switch B will automatically open and stop the machine.

The third hydraulic switch C is adapted to open whenever the operating load is less than a preferred minimum and of course at no load, but closes as soon as a pressure of substantially three hundred and fifty pounds is reached which corresponds to the load effected by simultaneously sizing five tubes. Since the minimum load of three hundred and fifty pounds is only reached during the sizing operation, it is necessary to provide means for maintaining the circuit closed until a set of mandrels having tubes telescoped thereon enters the sizing dies.

To this end, the switch C is used in conjunction with the above-described limit switch 153 which is normally closed to complete the circuit around the switch C. Consequently, even though the latter is open during the stripping operation, the circuit will remain closed and the machine will continue to operate. However, as soon as the sizing operation begins the limit switch will be operated by the aforesaid cam rollers 149 to momentarily open the circuit around the switch C. If at this moment, the working load is less than the three hundred and fifty pound minimum, then both the limit switch 153 and the pressure switch C will be open simultaneously thereby causing the machine to come to a stop. If the load is normal, the switch C will be closed and the machine will continue to operate.

Between the line starter L and the pump motor 202 is connected a second knife switch N, the leads of which are connected to a pair of line starters 1 each associated with one of the motors 48 of the carriages. Leads from each line starter are connected to the above described micro-switch 190 for automatically controlling rotation of the mandrels. When ribbed or fluted tubes are to be sized, the knife switch N is opened to disengage the mandrel motors 48.

Summary of operation

The operation of the machine has been described above in more or less detail, but briefly is as follows:

The tubes to be sized are fed into the hoppers 10 from the respective stacks 72 so that in each hopper one tube lies in each groove in the bottom thereof in axial alignment with the sizing die and its respective mandrel. The operator starts the machine by pressing and momentarily holding down the starter button S.

As the pressure builds up in the hydraulic cylinder, the piston is pushed either to the right or left depending on the setting of the reversing valve 160. Assuming the latter is set so that the carriage at the left end of the machine will move to the right, then as the carriage begins to move its mandrels telescope into respective tubes in the hopper. The friction fit between a tube and its mandrel will cause the tube to be displaced longitudinally slightly in the direction of movement of its mandrel until the end of the tube abuts its respective sizing die. With the ends of tubes abutting their respective dies, the mandrels then telescope into the tubes until the shoulders 381 of each mandrel engages the adjacent end of its

respective tube. Thereupon the tubes are advanced positively through the sizing dies. If each mandrel is provided with a tube, then a normal working load is effected and the circuit through the hydraulic switch C remains closed and the machine continues to operate despite the momentary opening of the limit switch 153. Moreover, assuming smooth walled tubes at substantially the moment the sizing operation begins, the micro-switch 192 is closed to initiate the rotation of the mandrels. Simultaneously, lubricant is supplied to the sizing dies by the nozzle 66. As the mandrels of the carriage at the left end of the machine are forcing their tubes through their respective sizing dies, the mandrels of the carriage at the right end of the machine are being stripped of their sized tubes.

After the tubes have been pushed through the sizing dies (the flow of lubricant having already stopped), the movement of the carriages is reversed as described above. Moreover, if the mandrels have been rotating they now cease to rotate. As the mandrels are withdrawn from the sizing dies, the slight radial expansion of the sized tubes will suffice to prevent the tubes from being drawn back through the sizing dies, and hence the tubes will be stripped off the mandrels and will fall by gravity down into the discharge chutes of the receptacles 119 and from thence into suitable baskets 125.

It should be pointed out that both sets of dies 49 may be of the same dimensions and profile or either set may differ from the other in these respects. Thus, the machine may be readily adapted to size tubes of different sizes simultaneously by providing different sets of mandrels 380 corresponding to the different die sets and feeding the proper size tube into the corresponding hoppers. Such changes may be readily made due to the facility with which the dies may be replaced in the die holders and the ease in providing the mandrel shanks 380' with extensions 380 of different diameter.

What is claimed is:

45. 1. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
50. 2. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
55. 3. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
60. 4. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
65. 5. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
70. 6. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.
75. 7. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; and means to actuate said mandrel rotating means to rotate said telescoped mandrel extension and tube during their passage through said die.

their passage through said die; and means to automatically stop the rotation of said mandrel after passing through said die.

3. A machine for sizing tubes comprising a bed; a carriage reciprocably mounted on said bed; a mandrel comprising an extension and a shank portion rotatably supported on said carriage; means carried by said carriage to rotate said mandrel; a die secured on said bed in axial alignment with said mandrel; means on said bed between said die and said mandrel to support a tube to be sized in axial alignment with said mandrel and said die; means to move said carriage along said bed to telescope said mandrel extension into said tube and to push the telescoped mandrel extension and tube through said die; means to actuate said mandrel rotating means to rotate said telescoped mandrel extension and tube during their passage through said die; and means associated with said carriage moving means to reverse the movement of said carriage along said bed to withdraw said mandrel from said die and simultaneously to strip the sized tube from said mandrel extension; and means to automatically stop the rotation of said mandrel during the stripping operation.

4. A machine for sizing tubes comprising a bed; a carriage reciprocably mounted on said bed; a mandrel comprising an extension and a shank portion supported on said carriage; a die secured on said bed in axial alignment with said mandrel; means to supply lubricant to said die; means on said bed between said die and said mandrel to support a tube to be sized in axial alignment with said mandrel and said die; means to move said carriage along said bed to telescope said mandrel extension into said tube and to push the telescoped mandrel extension through said die; and means actuated by the movement of said carriage along said bed to transmit lubricant to said lubricant supply means.

5. A machine for sizing tubes comprising a bed; a carriage member reciprocably mounted on said bed; a carriage secured at each end of said member; a mandrel comprising an extension and a shank portion supported in each carriage in a plane substantially parallel to the plane of said bed, the mandrel extension of one carriage being opposed to the mandrel extension of the second carriage; means to feed tubes to be sized between said opposed mandrel extensions and in axial alignment therewith; sizing dies supported on said bed in axial alignment with said axially aligned tubes and mandrels; and means to move said carriage member along said bed to telescope the mandrel extension of one carriage into its respective tube and to move the telescoped tube and mandrel extension through their respective sizing die in a tube sizing operation, the mandrel extension of said second carriage being arranged to simultaneously withdraw from its respective sizing die and strip off its sized tube.

6. A machine for sizing tubes comprising a bed; a carriage member reciprocably mounted on said bed; a carriage secured at each end of said member; a mandrel comprising an extension and a shank portion rotatably supported in each carriage in a plane substantially parallel to the plane of said bed, the mandrel extension of one carriage being opposed to the mandrel extension of the second carriage; means carried by each carriage to rotate its respective mandrels; means to feed tubes to be sized between said opposed mandrel extensions and in axial alignment therewith; sizing dies supported on said bed in axial alignment with said axially aligned tubes and mandrels; and means to move said carriage member along said bed to telescope the mandrel extension of one carriage into its respective tube and to move the telescoped tube and mandrel extension through their respective sizing die in a tube sizing operation, the mandrel extension of said second carriage being arranged to simultaneously withdraw from its respective sizing die and strip off its sized tube.

ment with said axially aligned tubes and mandrel extensions; means to move said carriage member along said bed to telescope the mandrel extension of one carriage into its respective tube and to move the telescoped tube and mandrel extension through their respective sizing dies in a tube sizing operation, the mandrel extension of said second carriage being arranged to simultaneously withdraw from its respective sizing die and strip off its sized tube; and means to actuate each mandrel rotating means to rotate said mandrel extensions during the tube sizing operation only.

7. In a machine for sizing tubes; mandrels for supporting tubes to be sized; sizing dies in axial alignment with said mandrels; means to deliver tubes successively into axial alignment with said mandrels and dies; hydraulic means to move said mandrels in a direction to telescope within said axially aligned tubes and to move the telescoped mandrels and tubes through said sizing dies in a tube sizing operation; and a hydrostatic switch associated with said hydraulic means and responsive to an abnormal working load during said sizing operation to automatically stop the mandrel moving means.

8. In a machine for sizing tubes; mandrels for supporting tubes to be sized; sizing dies in axial alignment with said mandrels; means to deliver tubes successively into axial alignment with said mandrels and dies; hydraulic means to move said mandrels in a direction to telescope within said axially aligned tubes and to move the telescoped mandrels and tubes through said sizing dies in a tube sizing operation; and means actuated by said mandrel moving means to supply lubricant to said dies during a predetermined period of said sizing operation.

9. In a machine for sizing tubes; mandrels for supporting tubes to be sized; sizing dies in axial alignment with said mandrels; means to deliver tubes successively into axial alignment with said mandrels and dies; hydraulic means to move said mandrels in a direction to telescope within said axially aligned tubes and to move the telescoped mandrels and tubes through said sizing dies in a tube sizing operation; a hydrostatic switch associated with said hydraulic means and responsive to an abnormal working load during said sizing operation to automatically stop the mandrel moving means; and control means for said hydraulic means to automatically reverse the direction of movement of said mandrel moving means to withdraw said mandrels from said dies and to strip off the sized tubes from said mandrels.

10. In a machine for sizing tubes; mandrels for supporting tubes to be sized; sizing dies in axial alignment with said mandrels; means to deliver tubes successively into axial alignment with said mandrels and dies; hydraulic means to move said mandrels in a direction to telescope within said axially aligned tubes and to move the telescoped mandrels and tubes through said sizing dies in a tube sizing operation; a hydrostatic switch associated with said hydraulic means and responsive to an abnormal working load during said sizing operation to automatically stop the mandrel moving means; control means for said hydraulic means to automatically reverse the direction of movement of said mandrel moving means to withdraw said mandrels from said dies and to strip off the sized tubes from said mandrels; and a discharge chute constructed and arranged to receive the sized tubes stripped from said mandrels and to deliver said tubes from said discharge chute at predetermined intervals.

11. In a machine for sizing tubes; a bed; a carriage reciprocably mounted on said bed; a mandrel supported on said carriage; means to deliver a tube to be sized into axial alignment with said mandrel; a sizing die supported on said bed in axial alignment with said axially aligned mandrel and tube; hydraulic means to move said carriage along said bed and telescope said mandrel into said tube and to move said telescoped tube and mandrel through said die in a tube sizing operation; and a hydrostatic switch associated with said hydraulic means and responsive to an abnormal working load during said sizing operation to automatically stop said carriage.

12. In a machine for sizing tubes; a bed; a carriage reciprocably mounted on said bed; a mandrel supported on said carriage; means to deliver a tube to be sized into axial alignment with said mandrel; a sizing die supported on said bed in axial alignment with said axially aligned mandrel and tube; hydraulic means to move said carriage along said bed and telescope said mandrel into said tube and to move said telescoped tube and mandrel through said die in a tube sizing operation; and means to supply lubricant to said dies during a predetermined period of the sizing operation.

13. In a machine for sizing tubes; a bed; a carriage reciprocably mounted on said bed; a mandrel supported on said carriage; means to deliver tubes to be sized successively into axial alignment with said mandrel, means associated with said tube delivering means and actuated by the movement of said carriage to temporarily support the tube next succeeding the tube delivered into axial alignment with the mandrel in vertically spaced relationship to prevent abrading action between the two tubes; a sizing die supported on said bed in axial alignment with said axially aligned mandrel and tube; and hydraulic means to move said carriage along said bed to telescope said mandrel into said axially aligned tube and to move said telescoped tube and mandrel through said sizing die in a tube sizing operation.

14. In a machine for sizing tubes; mandrels for supporting tubes to be sized; sizing dies in axial alignment with said mandrels; means to deliver tubes successively into axial alignment with said mandrels and dies; and means associated with said tube delivering means to tem-

porarily support the tubes next succeeding those which have been delivered into axial alignment with said mandrels in vertically spaced relationship to prevent abrading action therebetween.

5 15. In a machine for sizing tubes; a bed; a tube sizing die supported on said bed; means for feeding tubes successively into axial alignment with said dies; a balanced tube sizing and stripping mechanism embodying a carriage member reciprocably mounted on said bed and having a carriage at each end thereof; a set of mandrels supported in each carriage; and hydraulic means for reciprocating the carriage with respect to said tube feeding means and said sizing dies whereby 10 as one set of mandrels sizes a plurality of tubes the second set of mandrels strips off a plurality of sized tubes.

15 16. In a machine for sizing tubes; a bed; a tube sizing die supported on said bed; means for feeding tubes successively into axial alignment with said dies; a balanced tube sizing and stripping mechanism embodying a carriage member reciprocably mounted on said bed and having a carriage at each end thereof; a set of mandrels supported in each carriage; hydraulic means for reciprocating the carriage with respect to said tube feeding means and said sizing dies whereby 20 as one set of mandrels sizes a plurality of tubes the second set of mandrels strips off a plurality of sized tubes; and hydrostatic switches associated with said hydraulic means and responsive to an abnormal working load during a tube sizing operation to automatically stop said machine.

LESTER H. MESSINGER.
